(57) CLAIM

The ornamental design for a set of shoe pads, as shown and described.

DESCRIPTION

FIG. 1 is a top perspective view of a set of shoe pads, showing my new design;

FIG. 2 is a top elevational view thereof;

FIG. 3 is a front elevational view thereof;

FIG. 4 is a side elevational view thereof;

FIG. 5 is an opposite side elevational view thereof; and,

FIG. 6 is a rear elevational view thereof.

The broken lines in FIGS. 1-6 show unclaimed environmental subject matter only and form no part of the claimed design.
